US0D1017156S

(12) **United States Design Patent** (10) **Patent No.:** **US D1,017,156 S**
(45) **Date of Patent:** **** Mar. 5, 2024**

(54) **CLEANER**

(71) Applicant: **DUPRAY VENTURES INC.**, Montreal (CA)

(72) Inventors: **Michel Morand**, Verdun (CA); **Brent Gray**, Montreal (CA); **Guillaume Cavalié**, Montreal (CA)

(73) Assignee: **DUPRAY VENTURES INC.**, Montreal (CA)

(**) Term: **15 Years**

(21) Appl. No.: **29/837,848**

(22) Filed: **May 9, 2022**

(51) LOC (14) Cl. **15-05**

(52) U.S. Cl.

USPC **D32/21**

(58) **Field of Classification Search**

USPC D32/1, 15, 21, 24, 31; D21/526; D30/158; D13/108

CPC A47L 5/24; A47L 5/26; A47L 5/28; A47L 5/30; A47L 9/102; A47L 9/122; A47L 9/127; A47L 9/1608; A47L 9/1683; A47L 9/2857; A47L 9/2884; A47L 9/32; A47L 9/322; A47L 11/30; A47L 11/4016; A47L 11/4075; A47L 7/0009; A47L 9/327; B04C 5/185; B01D 2279/55; B23Q 11/0046; B23Q 11/0071; E04H 4/1636

(57) **CLAIM**

The ornamental design for a cleaner, as shown and described.

DESCRIPTION

FIG. 1 is a perspective view of a cleaner, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines shown in the figures is for the purpose of illustrating portions of the cleaner and form no part of the claimed design.

1 Claim, 7 Drawing Sheets
